UNITED STATES PATENT OFFICE.

MATIJA BESHENICH, OF BEATTY, PENNSYLVANIA, ASSIGNOR OF ONE-FOURTH TO JOHN TIRODOR AND ONE-FOURTH TO MIKE MOHANEK, BOTH OF GREENSBURG, PENNSYLVANIA.

NON-REFILLABLE BOTTLE.

1,327,133.

Specification of Letters Patent.

Patented Jan. 6, 1920.

Application filed September 11, 1919. Serial No. 323,107.

To all whom it may concern:

Be it known that I, MATIJA BESHENICH, a citizen of Jugo-Slavia, residing at Beatty, in the county of Westmoreland and State of 5 Pennsylvania, have invented certain new and useful Improvements in Non-Refillable Bottles, of which the following is a specification.

The primary object of the present invention resides in the provision of a non-refillable bottle in which a bottle of ordinary construction has a plug device receivable therein and retained by a cross head or arm associated with the inner end thereof for 10 engaging position with the throat of the bottle to prevent withdrawal of the closure plug.

A further object of the invention resides in the provision of a bottle of the non-refillable type wherein a neck plug insertible within the neck of a bottle is adapted to have an arm positioned transversely of the inner end of the plug for insertion within the bottle neck, and the arm permanently retaining 15 so positioned to prevent withdrawal of the neck plug.

With the above and other objects in view, the invention consists in the novel form, combination and arrangement of parts hereinafter more fully described and shown in the accompanying drawings, wherein like reference characters indicate similar parts throughout the several views.

In the drawings,

35 Figure 1 is a vertical sectional view of a non-refillable bottle constructed in accordance with the present invention, the arm for retaining the plug within the bottle neck being shown in full lines and separate from 40 the plug, the arm being shown in dotted lines in position in the plug,

Fig. 2 is a view similar to Fig. 1 with the bottle in inverted position, the cross arm locked in the neck plug and with the ball 45 valve unseated,

Fig. 3 is a vertical sectional view of a bottle similar to Fig. 1 with the bottle neck plug shown in elevation,

50 Fig. 4 is a side elevational view of the cross arm associated with the neck plug detached therefrom illustrating the method of loosely attaching cords to the arm for positioning the same in the neck plug,

Fig. 5 is a cross sectional view on line

V—V of Fig. 3 showing the gasket lock between the bottle neck and the neck plug,

Fig. 6 is a cross sectional view on line VI—VI of Fig. 3 showing the bottle neck and neck plug with the cross pins for limiting the outward movement of the ball valve,

Fig. 7 is a cross sectional view on line VII—VII of Fig. 3 showing the cross arm positioned in the neck plug, and

Figs. 8 and 9 are vertical sectional views of a modified form of the invention showing the cross arm secured to the inner end of the neck plug by a link with the separate finger carried by the neck plug for engagement with the cross arm.

Briefly described, the present invention 70 aims to provide a bottle closure of the non-refillable type wherein the neck of an ordinary bottle is provided with a plug that carries a valve and seat therefor, the plug extending beyond the neck of the bottle into 75 the body thereof and having a transverse opening into which an arm is adapted to be transversely inserted of said opening after the plug has been inserted within the bottle neck, cords being loosely associated with 80 the cross arm for correctly positioning the same in the plug opening. When the cross arm has been positioned as illustrated in the drawings, the cords may be detached therefrom and the cross arm will remain in its 85 fixed position inasmuch as the same is formed of fibrous material as wood that will be expanded when saturated with the fluid contents of the bottle and be permanently retained in position in the plug, thus to retain 90 the plug within the bottle neck and with the valve carried by the plug preventing fluid contents from again being introduced into the bottle but at the same time permitting an unrestricted flow from the bottle.

Referring more in detail to the accompanying drawings, there is illustrated a bottle 8 having a throat portion 9 and a neck 10, into which neck the plug 11 of hollow construction is adapted to be received with 100 an annular shoulder 12 upon its upper end adapted for seating upon the open upper end of the bottle neck 10, the plug being prevented from movement relative to said neck by the rubber gasket 13 seating in corresponding grooves in the opposed faces of the bottle neck and plug as is clearly illustrated.

The plug 11 comprises in detail, a cylindrical body portion having a tubular outer end into which an ordinary plug stopper may be inserted while the inner end of the 5 tubular portion is constructed to provide a valve seat 14 for a ball valve 15 co-operating therewith and having limited movement relative thereto, the cross pins 16 extending transversely of the plug 11 holding the ball 10 valve 15 in position within the plug recess. The extreme inner end 17 of the neck plug is connected to the outer part thereof by side bars 18, the inner end being provided with an arcuate transverse opening 19, having communication with the space between the spaced bars 18 by the central opening 20 formed in the upper wall thereof and positioned directly beneath the valve seat 14.

A cross arm 21 curved coincident to the 20 arc of the transverse opening in the extreme inner end of the neck plug and of a cross sectional area equal to said opening is adapted to be received in the opening so that the opposite ends thereof as illustrated in 25 Fig. 2 will be in a position to engage the throat of the bottle to prevent the withdrawal of the plug from the bottle neck, separate cords 22 and 27 being associated with the curved arm 21 and extending outwardly of the bottle for accomplishing this 30 result.

In mounting the plug within a bottle neck, the cord 22 is passed through the opening 24 in the curved arm and extended 35 around the adjacent end of the arm and seated within the end groove 25 and is tied in a single knot as at 26. Another cord 27 is passed through the opening 24 and extended around the other end of the arm 21 and is 40 seated within the end groove 28, the same being knotted as at 29. The four strands 22 and 27 of the cords are extended into the transverse opening 19 in the plug and thence through the opening 20 in the upper 45 wall of the opening 19 to extend upwardly between the side walls 18 through the valve seat 14, beyond the ball valve 15 and outwardly of the enlarged end 12 of the neck plug. The curved arm 21 is first inserted 50 through the bottle neck after the bottle has been filled with the desired liquid or other contents, to lie in the full line position shown in Fig. 1 with the neck plug properly seated as illustrated. To position the 55 curved arm 21 within the transverse opening 19 as illustrated in Fig. 2, the cord 27 is drawn outwardly of the bottle neck to cause the adjacent end of the curved arm 21 to register with the adjacent end of the opening 19 and by further pulling upon the cord 27 the arm 21 is moved into the opening 19 until the cord 27 at the end of said arm 21 is in line with the opening 20 at which 60 time the knot 29 will be disengaged by pulling upon one of the strands of the cord to 65

unthread the same from the arm 21 and entirely remove the cord from the bottle. A pulling strain at this time upon the arm 22 will cause the arm 21 to be moved farther into the slot to the dotted line position 70 shown in Fig. 1 which may be observed through the transparent glass wall of the bottle and when so arranged, pulling strain upon one of the strands of the cord 22 will release the knot 26 and permit this cord to 75 be entirely removed from the arm and bottle. With the arm in this position, and immersed within the fluid contents of the bottle, the same will be expanded by saturation and be effectively locked crosswise of 80 the plug 11 to prevent the withdrawal of the neck plug. In using the bottle, the fluid contents thereof may readily flow therefrom past the ball valve 15 which will leave its seat when the bottle is tilted and being limited in its unseating movement by engaging the cross pins 16, the bottle when reverted to upright position causing the seating of the valve 15 to prevent the refilling of the 85 bottle.

While there is herein shown and described the preferred embodiment of the invention it is nevertheless to be understood that minor changes may be made in the form, combination and arrangement of 90 parts without departing from the spirit and scope of the same as claimed.

The modification of the invention shown in Figs. 8 and 9 includes all of the structural details of the bottle as well as the neck plug 100 11, but in this form of the invention, the curved cross arm 21' is retained in the transverse opening 19 in the neck plug 11 by mechanical devices preventing movement thereof in opposite directions after being 105 positioned therein. The cross arm 21' is provided with an opening 30 in one end thereof in which one end of a link 31 is secured, the other end of the link being loosely connected to an apertured ear 32 formed at 110 the inner end 17' of the plug 11. The bottom wall of the transverse opening 19 has secured thereto as at 33 a spring finger 34 that is adapted when the curved arm 21' is positioned in the opening 19 to have the resilient projecting end thereof engaged in the notch 35 formed upon the lower face of said arm. To shift the cross arm 21' from the position shown in Fig. 8 to that shown in Fig. 9, there is provided a cord 36 loosely 115 passing through the opening 37 in the curved arm 21, the cord being threaded through the plug 11 as illustrated in Fig. 1 so that upon a pull on the cord 36, the free end of the arm 21 is caused to be drawn into the opening 19 and continued movement of the cord causes the arm to move through said opening in opposition to tension thereon from the spring 34 to a point observant 120 through the bottle where the spring finger 130

engages in the notch 35, at which time the cord 36 may be removed from the cross arm and plug and the bottle function as described in connection with the preferred 5 forms of the invention shown in Fig. 1.

What is claimed as new is:—

1. A device of the class described comprising a bottle, a plug inserted within the bottle, an arm adapted to be transversely positioned relative to said plug after insertion 10 within the bottle to prevent removal of said plug, said arm being curved downwardly and the positioning means therefor including a plurality of cords loosely attached 15 thereto and extending outwardly of the bottle neck.

2. A device of the class described comprising a bottle, a plug insertible within the neck thereof, said plug having a curved 20 transverse opening in its inner end and a curved arm positioned in said plug opening after insertion within said bottle neck to prevent withdrawal thereof, and cords extending outwardly of the bottle neck through the 25 plug.

3. A device of the class described comprising a bottle, a plug insertible within the neck

thereof, said plug having a transverse opening in its inner end, a cross arm carried by said plug and adapted to be positioned in 30 said transverse opening, coöperating means at said plug and cross arm to prevent withdrawal of the cross arm from said plug opening, said coöperating means including a 35 spring finger carried by the plug and an engaging recess upon the adjacent face of said cross arm for said spring finger.

4. A device of the class described comprising a bottle, a plug insertible within the neck thereof, said plug having a transverse 40 opening in its inner end, a cross arm carried by said plug and adapted to be positioned in said transverse opening, coöperating means at said plug and cross arm to prevent withdrawal of the cross arm from said plug 45 opening, and means carried by said cross arm adapted to be removed therefrom for placing said cross arm in the plug opening, said means being adapted for removal from 50 said bottle after positioning the arm in said opening.

In testimony whereof I affix my signature.

MATIJA BESHENICH.
